VALVE RESURFACING MECHANISM

Filed Nov. 24, 1925

UNITED STATES PATENT OFFICE.

ROBERT E. LEES, OF WILLIAMSBURG, PENNSYLVANIA.

VALVE-RESURFACING MECHANISM.

Application filed November 24, 1925. Serial No. 71,147.

The present invention relates to mechanisms for resurfacing or polishing valve seating surfaces. More specifically it relates to a mechanism to be used in connection with valves of internal combustion engines which have a beveled seat or surface which is apt to become pitted or burned, necessitating more or less frequent surfacing.

An object of the present invention is the provision of a mechanism adapted to be mounted on a power-driven device, which mechanism holds the valve and provides means for producing an accurate and true surface on the seating of the valve.

15 A further object is the provision of an adjustable mechanism for resurfacing valves of various diameters and sizes.

In the accompanying drawings which form a part of the present specification:—
20 Figure 1 shows a sectional view of the mechanism mounted in place upon an electric drill;

Fig. 2 shows a top plan view of the same; and

25 Fig. 3 a view from the direction of the arrows 3—3 in Fig. 1.

The specific form of the invention illustrated includes a supporting member or frame 1 which has at its outer end an orifice 30 2 into which a removable bushing 3 fits, the same being held in position by means of a set screw and lock nut 4. A plurality of bushings adapted to fit various sized valve stems are provided and the proper size may 35 be therefore readily selected and fastened in the orifice 2.

The supporting member 1, as shown in Fig. 2, has a slot 5 cut in its inner end, the inner end having a surface 1^a to fit accurately upon the cylindrical surface of an electric drill 6. A clamping nut 7 co-operates to tighten the split portion of the supporting member in position on the electrical drill so that the bushing 3 is in axial alignment with the chuck 8 of the drill. A supporting arm 9 is provided at the front end of the supporting member to one side of and adjacent the bushing. This supporting arm carries a roller 10.

50 A second supporting arm 11 is also provided at the front end of the supporting member. This arm is bifurcated at its outer end, the lower bifurcation 12 having a threaded opening adapted to receive an adjusting screw 13. The upper bifurcated

portion of the arm has a block 14 pivotally mounted thereon by means of a pivot 15. The upper surface of the block 14 is located in the same plane as the axis of the roller 10, the block and the roller providing a 60 plane resting surface for a file or similar cutting or polishing tool 16. The angle formed by this plane with respect to the axis of the bushing is the same as that commonly existent between the seating portion of an 65 internal combustion engine valve and its stem.

A spring 17 is provided between the outer end of the block 14 and the lower portion of the bifurcated arm 12 so that the inner end 70 of the block is biased toward the adjusting screw 13. It is therefore possible by means of this adjusting screw to raise or lower the front end of the block 14 which has its upper surface cam-shaped or curved, and to 75 thereby raise or lower the file or tool 16 with respect to the axis of the valve to be operated upon without in any way altering its angular relation. By this adjustable means different sized valves may 80 easily be accommodated.

In making use of the device, the supporting member 1 is clamped, by means of the clamping screw 7, in such a position upon an electric drill, with the bushing orifice 2 85 in axial alignment with the chuck of the drill, the electric drill being held in a suitable base or vise 18. A proper size bushing for the valve to be operated upon is then selected and locked in place by the set screw 90 4. The valve 19 is then inserted in the bushing member and its stem is fixed in the chuck 8 of the drill, this manipulation being carried on through the openings or cut-away portions 20 formed in the sides of the 95 supporting member 1. The drill is started and the valve is rapidly rotated by means of the drill chuck. A file 16 is laid across the roller 10 and the block 14, the block having been previously adjusted so that the file makes a very light contact with the edge of the valve. The depth of cut on the surface of the valve is then regulated by means of the adjusting screw 13 and the resurfacing operation carried out. For subsequent 100 polishing the surface of the valve, a stone, or block of wood covered with emery paper, may be substituted for the file while the valve is rotating.

105 It is of course understood that various 110

changes and modifications from the specific disclosure may be made within the scope of the appended claims.

What I claim is:

- 5 1. In a valve resurfacing attachment, a supporting member, a valve guide located in one end of said supporting member, a pair of tool supports carried by said supporting member adjacent said valve guide, and positioning and clamping means located at the other end of said supporting member for mounting the same on a power device having a rotatable chuck with said valve guide in axial alinement with said chuck.
- 10 2. In a valve resurfacing attachment adapted for use with a power device having a rotatable chuck, the combination of a supporting member, a valve supporting bushing located in one end of said supporting member, means for locking said bushing in place, a pair of tool supports carried by said supporting member adjacent said bushing, and positioning and clamping means located at the other end of said supporting member for mounting the same on said power device with said bushing in axial alinement with said chuck.
- 15 3. In a valve resurfacing attachment adapted for use with a power device having a rotatable chuck, the combination of a supporting member, a valve supporting bushing located in one end of said supporting member, means for locking said bushing in place, a pair of tool supports carried by said supporting member adjacent said bushing, and positioning and clamping means located at the other end of said supporting member for mounting the same on said power device with said bushing in axial alinement with said chuck.
- 20 4. In a valve resurfacing attachment adapted for use with a power device having a rotatable chuck, the combination of a supporting member, a valve supporting bushing located in one end of said supporting member, means for locking said bushing in place, a pair of tool supports carried by said supporting member adjacent said bushing, and positioning and clamping means located at the other end of said supporting member for mounting the same on said power device with said bushing in axial alinement with said chuck.
- 25 5. In a valve resurfacing attachment adapted for use with a power device having a rotatable chuck, the combination of a supporting member, a valve supporting bushing located in one end of said supporting member, means for locking said bushing in place, a pair of tool supports carried by said supporting member adjacent said bushing, and positioning and clamping means located at the other end of said supporting member for mounting the same on said power device with said bushing in axial alinement with said chuck.
- 30 6. In a valve resurfacing attachment, the combination of a supporting member, means to support a valve-stem rotatably in said member, a pair of tool supports carried by said member and means to vary the plane of said tool supports with respect to the axis of said valve stem.
- 35 7. In a valve resurfacing attachment, the combination of a supporting member, means to support a valve-stem rotatably in said member, a pair of tool supports carried by said member and a cam adjustably mounted on one of said tool supports.
- 40 8. In a valve resurfacing attachment, the combination of a supporting member, means to support a valve-stem rotatably in said member, a pair of tool supports carried by said member and a cam adjustably mounted on one of said tool supports.
- 45 9. In a valve resurfacing attachment adapted for use with a power device having a rotatable chuck, the combination of a sup-

porting member, a valve supporting bushing located in one end of said supporting member, a pair of tool supports carried by said supporting member adjacent said bushing, means for adjusting the height of one of said tool supports with respect to the axis of said bushing, and positioning and clamping means carried by the other end of said supporting member for mounting the same on said power device with said bushing in axial alinement with said chuck.

50 5. In a valve resurfacing attachment adapted for use with a power device having a rotatable chuck, the combination of a supporting member, a valve supporting bushing located in one end of said supporting member, a fixed tool support carried by said supporting member adjacent said bushing, a second tool support carried by said supporting member adjacent said bushing on the opposite side of the axis of said bushing from said first tool supporting member, adjustable means carried by said second tool support, and positioning and clamping means located at the other end of said supporting means and including a threaded member for mounting the same on said power device with said bushing in axial alinement with said chuck.

55 6. In a valve resurfacing attachment, the combination of a supporting member, means to support a valve-stem rotatably in said member, a pair of tool supports carried by said member and means to vary the plane of said tool supports with respect to the axis of said valve stem.

60 7. In a valve resurfacing attachment, the combination of a supporting member, means to support a valve-stem rotatably in said member, a pair of tool supports carried by said member and a cam adjustably mounted on one of said tool supports.

In testimony whereof, I have hereunto affixed my signature.

ROBERT E. LEES.
